UNITED STATES PATENT OFFICE.

ROY D. JEFFRIES, OF GRANADA, MINNESOTA.

DUST-CAP FOR HUBS.

1,303,066.

Specification of Letters Patent.

Patented May 6, 1919.

Application filed December 1, 1917. Serial No. 204,934.

To all whom it may concern:

Be it known that I, Roy D. JEFFRIES, a citizen of the United States, residing at Granada, in the county of Martin and State 5 of Minnesota, have invented new and useful Improvements in Dust-Caps for Hubs, of which the following is a specification.

This invention comprehends the provision of a sand band for use in connection with 10 a stub axle of motor vehicles to prevent dirt and other foreign substances from gaining access into the hub and bearings of the wheel.

The chief characteristic of the invention 15 resides in the provision of a device of the above mentioned character, which is designed to effectively prevent the admittance of dirt or the like into the hub of the wheel and one which can be quickly and easily 20 associated with the spindle and hub of the wheel without necessitating the use of tools, or fastening elements to maintain the band operatively associated with said parts.

The nature and advantages of the invention 25 will be better understood when the following detail description is read in connection with the accompanying drawing, the invention residing in the construction, combination and arrangement of parts as 30 claimed.

In the drawing forming a part of this specification like numerals of reference indicate similar parts in the several views and wherein:—

35 Figure 1 is a sectional view taken through a wheel hub showing the device forming the subject matter of my invention associated therewith and with the spindle.

Fig. 2 is a detail view of the band.

40 Referring more particularly to the drawing in detail A indicates generally the spindle provided with the usual shoulder B and cone bearing C, while the hub of the wheel is indicated generally at D 45 and includes an annular exteriorly disposed flange E.

The protector forming the subject matter 50 of my invention is in the nature of a pressed metal cup which is provided with a central opening 10 of suitable dimensions and snugly receives the spindle A, while the center portion of the protector is depressed as at 11 to accommodate the shoulder B against which the center portion of the 55 protector bears, partly embracing the latter as

clearly shown in Fig. 1. The protector is further formed to provide an annular flange 12 which is concentrically disposed about the adjacent end of the hub D, snugly contacting the latter to prevent dirt and other 60 foreign matter from gaining access into the hub of the wheel. The protector is rendered more effective for this purpose by reason of the fact that the flange bears against the flange E on the hub. The flange 12 defines 65 with the wall 13 of the depression 11, a groove 14 which is adapted to receive an annulus of suitable packing 15, so that when the protector is mounted upon the spindle as shown in Fig. 1 the packing 15 not only 70 prohibits the admittance of dirt and other foreign matter into the hub of the wheel, but also serves to space the hub from the protector, and maintain the lubricant in a clean fresh condition. A protector constructed in accordance with my invention 75 may be readily and easily associated with the spindle without necessitating the use of tools. In this connection it will be noted that the protector as hereinabove stated rests 80 against the shoulder B of the spindle partly embracing the latter, and when the cone bearing C is placed upon the spindle in its operative position, it serves to maintain the protector in its operative position, thus 85 eliminating the necessity for use of additional fastening means.

While it is believed that from the foregoing description the nature and advantages of the invention will be readily apparent, I 90 desire to have it understood that the same is merely illustrative of the preferred embodiment of the invention, which I do not consider restrictive, inasmuch as such changes may be resorted to when desired as 95 fall within the scope of what is claimed.

What is claimed is:—

A dust cap for use on a motor vehicle stub axle, said cap having a circumferential flange to engage around the inner end of a 100 wheel hub and also having a conical recessed portion to receive the shoulder of the axle and an inwardly extending annular flange at the smaller end of the depressed circumferential flange being such as to cause an 105 annular chamber to be formed between the wheel hub and the cup for the reception of packing.

In testimony whereof I affix my signature.

ROY D. JEFFRIES.
